United States Patent Office.

ALVAH L. SAWYER AND WILSON BALDWIN, OF DETROIT, MICHIGAN.

Letters Patent No. 78,397, dated May 26, 1868.

IMPROVED SPRING-BED BOTTOM.

The Schedule referred to in these Letters Patent and making part of the same.

TO WHOM IT MAY CONCERN:

Know all men that we, ALVAH L. SAWYER, and WILSON BALDWIN, of Detroit, in the county of Wayne, and State of Michigan, have invented a new and useful Improvement in Spring-Bed Bottoms; and we do declare that the following is a true and accurate description thereof, reference being had to the accompanying drawings, and to the letters of reference marked thereon, and being a part of this specification.

This invention consists in so arranging a series of transverse and longitudinal bars as to produce a strong, compact, elastic, and economical bed-bottom.

Figure 1 is a perspective view of our invention, and

Figure 2 a transverse sectional view on the line xx in fig. 1.

The same letters refer to like parts in each figure.

We use two transverse bars, A A, to which we attach the longitudinal bars B B. Upon these latter-named bars, and about equidistant from their ends, we place the fulcrum-blocks C C C, and in the centre we place the crotched spring D, extending transversely between the bars B. Then we fasten to the top of the blocks C and crotched spring D other longitudinal bars, E E, which are also attached at their ends to transverse bars F F, which sustain the slats H H H, &c.

These bed-bottoms can be made of any suitable size, and from any suitable material.

What we claim as our invention, and desire to secure by Letters Patent, is—

The combination of the transverse bars A A and F F, the longitudinal bars B B and E E, with the fulcrum-blocks C C C, the crotched transverse spring D, and the slats H H H, &c., when constructed, arranged, and operating substantially as herein set forth and shown.

ALVAH L. SAWYER,
WILSON BALDWIN.
